CLAIM

The ornamental design for a case, as shown and described.

DESCRIPTION

FIG. 1 is a top front perspective view of a case, showing the case in an open position, showing our new design;

FIG. 2 is a bottom rear perspective view thereof;

FIG. 3 is a front view thereof;

FIG. 4 is a rear view thereof;

FIG. 5 is a bottom view thereof;

FIG. 6 is a top view thereof;

FIG. 7 is a left side view thereof; and,

FIG. 8 is a right side view thereof.

The Figures are illustrated to show color contrast. The concave portion of the case and opposing side when the case is in an open position is light gray. The outer edge of the concave portion of the case and the rear surfaces are a darker gray.

1 Claim, 3 Drawing Sheets
